HAIG KAPIGIAN, OF CAMDEN, NEW JERSEY.

SHIP STABILIZER.

Application filed January 20, 1928. Serial No. 248,193.

The present invention relates to an improved stabilizer for ships, either sea-going vessels or life boats or for aeroplanes, the purpose being to provide pontoons arranged 5 on the sides of the body of the ship or aeroplane and provided with extensible means whereby the pontoons may be extended laterally of the body of the hull or returned to the side of the body of the hull accordingly as 10 may be desired.

Another purpose is to provide improved means for extending or retracting the pontoons.

Another purpose is to provide means 15 formed in the sides of the hull for the reception of the pontoons when they are retracted, the pontoons when rendered extensible acting to stabilize the ship, namely to overcome the side, fore and aft roll of the ship, 20 thereby producing buoyancy for the ship.

Another purpose is to provide, in a device of this kind, a construction wherein the resistance that the pontoons may offer to the swift passage of the vessel may be off-set to 25 a substantial amount.

Still another purpose is to provide a stabilizer of this character including pontoons which may be weighted in any manner, substantially thirty-one (31) pounds per cubic 30 foot, or any substantial suitable means being devised for varying the weight in the pontoons.

It is well established that when aeroplanes are traveling over seas and a forced 35 landing is necessary the pilot or operator has no way of insuring safety for a substantial period. If aid is not received for the unfortunate one in danger, the aeroplane though it may remain afloat for quite awhile, will eventually sink. Obviously a plane in 40 this particular instance may be easily destroyed before aid might be rendered. Hence it is still another purpose of the present invention to provide a stabilizer, which 45 is applicable to an aeroplane as well as to the sides of a ship's hull.

It is to be understood that the particulars herein given are in now way limitative, and that while still keeping within the scope of 50 the invention, any desired modification of details and proportions may be made in the construction of the appliance according to circumstances.

The invention comprises further features 55 and combination of parts to be hereinafter

set forth, shown in the drawings and claimed.

In the drawings:—

Figure 1 is a plan view of a vessel or boat embodying the improved stabilizer. 60

Figure 2 is a transverse vertical sectional view of Figure 1, showing the pontoons extending laterally.

Figure 3 is an end view of a vessel with the lower part of its wall partly in section 65 showing the pontoons retracted within the sides of the ship's hull.

Figure 4 is a sectional view through the ship's hull showing transverse openings formed through the hull of the ship, and 70 through said openings the waves may enter to decrease fore and aft pitching.

Figure 5 is a plan view showing the pontoons as applied to a life boat, in which case a manually operated winch may be used for 75 extending or retracting the pontoons.

Figure 6 is a detail view with parts in elevation and parts in section showing the means for extending the pontoons laterally.

Figure 7 is a plan view of a conventional 80 type of aeroplane showing the pontoons applied.

Referring to the drawings, 1 identifies a ship's hull, which may be any size, any shape, or it may be the hull of a life boat, and 85 which hull is provided in its sides with cavities or recesses or spaces 2 for the reception of pontoons 3. These pontoons are hollow and are capable of rendering the ship's hull buoyant, and therefore when extended act to prevent the side roll of the ship's hull. 90

Each pontoon may, as in Figure 1, be made in sections, though not necessarily, as it is obvious that the pontoon on each side 95 may be in one piece.

However each section constitutes a pontoon, and in such an instance one end of a section may have an inturned portion 4, which receives the conical end 5 of an adjacent section. 100

The pontoons are rendered extensible and to accomplish this result they are carried on racks 6 which telescope within tubes 7, which have exterior rack teeth 8. The tubes 105 7 with their teeth 8 are mounted in guides 9 in the sides of the hull in any convenient manner and may be maintained in guided positions in any well-known way.

The tubular racks operate transversely of 110

the ship's hull, while the racks 6, when entirely received within the tubular racks 7 also assume a transverse position of the ship's hull. The outer ends of the racks 6 are secured to the pontoons as at 10, hence in this manner the pontoons are supported laterally of the ship's hull, and the sections thereof in alignment, thereby acting to stabilize the ship's hull when extended.

Secured within the ship's hull on one of its decks, possibly as shown at 11 in Figure 6, is a bearing 12 which carries a fulcrum 13, on which an arm 14 is adapted to swing. The outer end of this arm carries a stub shaft 15 provided with a gear 16 and a sprocket 17. The gear 16 may mesh with the teeth of the rack 6 or with the teeth 8 of the tubular rack 7. The fulcrum or pivot 13 carries a pulley 18 and a sprocket 19, the latter being engaged by a sprocket chain 20, which operates about the sprocket 17.

Arranged in the hull adjacent the bearing 12 secured at 21 is the base of a motor 22, which receives current through the wires 23 from any suitable source. This motor 22 has a shaft 24 provided with a pulley 25, and with which a belt 26 engages. This belt passes about the pulley 18. Power being transferred through the wires 23, the belt transmits power to the fulcrum or shaft 13 which in turn through the medium of the sprocket 19 and the sprocket 20, power is transmitted to the gear 16. Since the gear 16 meshes with the teeth of the rack 6 or with the teeth of the tubular rack 7, the two racks 6 and 8 may be extended, and the pontoons projected beyond the sides of the ship's hull.

Each of the racks 7 are operated by a similar means as shown in Figure 6. When the rack 7 is extended to its limit, the gear 16 transmits power to the rack 6 and the latter is then extended. When the pontoons are retracted they seat within the recesses or cavities 2, which extend longitudinally of the sides of the ship's hull.

As shown in Figures 1 and 4 the ship's hull is provided with transverse openings 27, which offset to some extent the fore and aft pitching of the ship. These openings have tapered or inclined sides as shown, and certain walls of the openings are provided with fins 28, which also act to offset to some extent the fore and aft pitching of the ship, due to the traveling of the water back and forth through the openings.

The waves during the passage of the ship's hull through the water, break or are otherwise shunted within the openings, and due to the fins or blades the waves are broken up. These openings or passages 27 may be in any portion of the ship's hull, preferably where the bottoms of the openings may be approximately at normal water level, it being the fact that when the sea is rough the waves will break through the openings and

thereby overcome fore and aft pitching and hence keep the ship on an even keel.

As shown in the drawing particularly Figure 5, pontoons are applied to life boats as well as to the sides of the fuselage of an aeroplane, or depending from the bottom of the fuselage 29 as shown in Figure 7.

As shown in Figure 5 the pontoons 3^a are curved and tapered as shown, to conform to the sides of the life boat. The pontoons 3^a in Figure 5 have racks 30, which cooperate with the gears 31, the shafts 32 on which are sprockets 33. The sprockets 33 are engaged by sprocket chains 34, which in turn are operated by the sprockets 35 and 36, which are carried on the crank shaft 37. The shaft 37 carries two sprockets, there being a shaft 37 at each end of the life boat. Each shaft 37 carries a crank 38. By rotating the crank motion will be imparted to the shafts 32 and thence motion is imparted to the gears 31 and then to the racks 30, whereby the pontoons may be extended or retracted.

The same arrangement for extending the pontoons 3^a in Figure 5 may be used for extending and retracting them in Figure 7, where the pontoons are applied to an aeroplane. However an auxiliary sprocket chain 39 cooperates with a sprocket 40, which is carried by a shaft 41, and sprockets 42 for transmitting power to the sprocket chains 43. The sprocket chain 39 is operated by sprockets 44 and crank shaft 45. By rotating the crank of the shaft 45 motion may be imparted to the chain 39 and thereby extend or retract the pontoons in Figure 7.

Suitable guy wires 47 as shown in Figure 2 are connected to the outer ends of the racks and have their inner ends operatively connected with spring drums 48, whereby the guy wires may be wound up when the racks are retracted.

The invention having been set forth what is claimed is:

1. In a stabilizer as set forth, a floating body, a plurality of pontoons arranged relatively to the sides of the body, said pontoons consisting of a plurality of sections in axial alignment, one section fitting into the other, the sides of the body having cavities for the reception of the pontoons when retracted, extensible means connecting the pontoons to the sides of the body, said extensible means comprising telescoping racks, certain of the racks mounted in guides of the sides of the body, and mechanisms including gears and motors with operative connections between the motors and gears for extending and retracting the racks.

2. In a stabilizer as set forth, a floating body, a plurality of pontoons arranged relative to the sides of the body, said pontoons consisting of a plurality of sections, the sides of the body having cavities or re-

cesses for the reception of the pontoons when retracted, extensible means comprising telescoping racks connecting the pontoons and the sides of the body, guy wires connecting the outer ends of the racks and the sides of the body to assist in supporting the racks and the pontoons, and mechanisms including motors and gears with operative connections between the motors and the gears, the gears adapted for operative connections with the racks for extending and retracting the pontoons.

3. In a stabilizer, the combination with a

floating body, of pontoons arranged relatively to the sides of the body, extensible means consisting of telescoping racks, certain of which being connected to the pontoons and others of which mounted in guides of the body, and mechanisms including gears for operating the racks for extending and retracting them, whereby the pontoons are extended and retracted.

In testimony whereof he affixes his signature.

HAIG KAPIGIAN.
